UNITED STATES PATENT OFFICE

CHARLES L. SEBRING, OF SEBRING, OHIO, ASSIGNOR TO LEIGH POTTERS, INC., OF ALLIANCE, OHIO, A CORPORATION OF OHIO

DESIGN FOR A PLATE OR SIMILAR ARTICLE

Application filed October 26, 1929. Serial No. 33,174. Term of patent 14 years.

To all whom it may concern:

Be it known that I, CHARLES L. SEBRING, a citizen of the United States, residing at Sebring, in the county of Mahoning and State of Ohio, have invented a new, original, and ornamental Design for Plate or Similar Article, of which the following is a specification, reference being had to the accompanying drawing, forming part hereof.

Fig. 2, a side elevation of the plate.

I claim:

The ornamental design for a plate or similar article, as shown.

CHARLES L. SEBRING.
